UNITED STATES PATENT OFFICE.

JOHN EDMAN, OF MINNEAPOLIS, MINNESOTA, ASSIGNOR TO EDMAN CAR DOOR COMPANY, OF MINNEAPOLIS, MINNESOTA, A CORPORATION OF MINNESOTA.

LOCK FOR CAR-DOORS.

1,112,899.

Specification of Letters Patent.

Patented Oct. 6, 1914.

Application filed December 9, 1912. Serial No. 735,661.

To all whom it may concern:

Be it known that I, JOHN EDMAN, a citizen of the United States, residing at Minneapolis, in the county of Hennepin and State of Minnesota, have invented certain new and useful Improvements in Locks for Car-Doors; and I do hereby declare the following to be a full, clear, and exact description of the invention, such as will enable others skilled in the art to which it appertains to make and use the same.

My invention relates to car doors and is particularly directed to the improvement in the construction of certain of the parts of car doors of the general type disclosed in my prior Patent 884,011, of date, April 7th, 1908, entitled "Grain door for cars."

Generally stated, the invention consists of the novel devices and combinations of devices hereinafter described and defined in the claims.

In car doors of the type above noted, pivoted lock blades, so-called, are employed to hold the doors in working positions and against outward swinging movements. Hitherto, I have found it desirable to cast these lock blades and to form the same with tubular backs to obtain strength and lightness. In the formation of these tubular backs, very long cores are necessary, and this makes the blades thus cast, expensive.

One feature of my present invention provides an improved construction of the lock blade whereby it may be cast without cores and still have the desired strength and lightness.

In the accompanying drawings which illustrate the invention, like characters indicate like parts throughout the several views. Referring to the drawings, Figure 1 is a fragmentary view in side elevation showing the improved lock blade applied to a car in connection with the car door; Fig. 2 is a horizontal section on an enlarged scale taken on the line x^2x^2 on Fig. 1; Fig. 3 is an end plan view of the lock blade; and Fig. 4 is a side elevation of the same, some parts being broken away.

The numeral 1 indicates the car body and 50 the numeral 2 the car door, which latter is seated in one of the side door openings of said car and is adapted to swing outward, but is normally held against outward swinging movements, by a pair of my improved 55 lock blades, one on each side of the door

opening. These lock blades are formed with door engaging flanges 3 and with channeled backs 4, which latter take the place of the tubular backs hitherto employed. These channel-shaped backs 4, at their upper and lower ends, are formed with trunnions 5 that are seated in suitable upper and lower bearings 6 and 7, suitably secured to the car body, preferably to the door posts thereof. At suitable intervals longitudinally thereof, the channel-back 4 is provided with transverse stiffening ribs 8. The edges of the door 2 are normally held between the flanges 3 of the lock blades, and the inner flanges of metallic channel beams 9, that are rigidly secured to the door posts 1^a of the car body, just inward of the channel backs of the said lock blades. Smaller channel irons or bars 10 are secured to the door posts just outward of the channel irons or bars 9. These channel bars 9 and 10 form a sort of housing for the channel backs of the lock blades, and the outer angle bars 10 afford abutments against which the outside flanges of the channel backs of the lock blades can be sprung under extreme pressure from the load within the car, acting against the door 2. The two extreme positions of the lock blade are illustrated by full lines and by dotted lines in Fig. 2.

As is evident, in the lock blade described and illustrated in the drawings, the two-part flask is capable of being molded from the sand, and hence, may be cast in a two-part flask and without the use of cores.

What I claim is:

1. The combination with a car, and a car door movable through a door opening in the body of said car, of inner and outer vertically extended bars secured to the sides of the door opening, and a lock blade pivotally mounted to work between said bars and operative to secure said door against the inner of said bars and to release the same, said lock blade having a longitudinally extended flange offset from its pivotal axis and engageable with said outer bar when said lock blade is in operative position.

2. The combination with a car, and a car door movable through a door opening in the body of said car, of inner and outer vertically extended bars secured to the sides of the door opening, and a lock blade pivotally mounted to work between said bars, and having a channel-shaped back, said lock

blade being operative to secure said door against the inner of said bars and to release the same, the flanges of the channel-shaped back of said lock blade being alter-
nately engageable with opposite sides of the outer of said bars when said lock blade is in either an operative or an inoperative position.

3. The combination with a car, and a car door movable through a door opening in the body of said car, of relatively wide inner and relatively narrow outer vertically extended bars secured to the sides of said door opening, and a lock blade pivotally mounted to work between the said bars, and operative to secure said door against the relatively wide bar and to release said door for movement outward past said relatively narrow bar, said lock blade having a laterally projecting flange extending between said bars and engageable with said relatively

narrow bar when said lock blade is in an operative position.

4. The combination with a car and a car door movable through a door opening in said car body, of relatively wide inner and relatively narrow outer vertically extended angle bars secured to the sides of said door opening, lock blades pivotally mounted to work between the extended flanges of said inner and outer angle bars, and operative to secure said door against the flange of the relatively large inner angle bars, and to release said door for movements outward past said relatively narrow outer angle bars. 35

In testimony whereof I affix my signature in presence of two witnesses.

JOHN EDMAN.
